UNITED STATES PATENT OFFICE.

NOAH E. MEREDITH, OF LOS ANGELES, CALIFORNIA.

VALVE-GRINDER.

1,015,902.

Specification of Letters Patent.

Patented Jan. 30, 1912.

Application filed November 18, 1911. Serial No. 661,148.

To all whom it may concern:

Be it known that I, NOAH ELLSWORTH MEREDITH, a citizen of the United States, residing at Los Angeles, in the county of Los Angeles and State of California, have invented a new and useful Valve-Grinder, of which the following is a specification.

This invention relates to valve grinders adapted for grinding the valve of internal combustion engines, and the main object of the invention is to provide means for this purpose which is simple in construction and effective in operation.

This invention relates more particularly to a valve grinder adapted to produce alternating angular movements of the valve in opposite directions in such manner that the movements in one direction are greater than those in the opposite direction, and a further object of the invention is to provide improved means for producing such motion by the operation of a continuously rotated shaft extending at right angles to the operated spindle of the valve grinder.

Other objects of the invention will appear hereinafter.

The accompanying drawings illustrate the invention, and referring thereto: Figure 1 is a side elevation of the valve grinder showing in vertical section, a portion of an engine casing with the valve therein in cooperative relation with the grinder. Fig. 2 is a vertical section of the valve grinder. Fig. 3 is a vertical section on line x^3-x^3 in Fig. 2. Fig. 4 is a vertical section on line x^4-x^4 in Fig. 2. Fig. 5 is a horizontal section on line x^5-x^5 in Fig. 2. Fig. 6 is a view similar to Fig. 5, showing a different position of the operating parts. Fig. 7 is a perspective showing a modified form of the operating member. Fig. 8 is a perspective showing another modification of the operating member.

Referring to Figs. 1 to 6, the device comprises a form composed of a body portion 1 and a casing 4 screwing on to said body portion as shown at 5, a vertical spindle 2 journaled in a vertical bearing 3 in said body 1, a driving shaft 6 journaled in bearings 7 in said casing 4, and provided with an operating handle or crank 8, and inter-engaging devices on said operating or driving shaft 6 and on the spindle 2 for producing alternate forward and back movements of the spindle by continuous rotation of the driving shaft. Casing 4 is formed

with a handle portion 9 consisting of a tubular upward extension from said casing and said tubular extension being closed and being provided if desired, with a removable screw-plug 10 to facilitate oiling.

The operated spindle 2 carries at its upper end, a crown wheel 11, formed as a disk having upwardly projecting teeth 12, said teeth being preferably round or conoidal and the driving shaft 6 is provided with two sets of arms or teeth 13 and 14 engaging respectively with the teeth 12 of the crown wheel at the opposite sides of the center or axis of the spindle 2. These sets of teeth 13 and 14 may be formed as projections from a single sleeve 15, secured to the shaft 6 by a set-screw 17, such construction rendering the angular relation of the said sets of teeth permanent. There may be any desired number of teeth in each set, for example, three teeth, as shown in Figs. 3 and 4, in each set, and said teeth in the respective sets are angularly displaced so that the teeth of one set are staggered or arranged alternately with relation to the teeth of the other set, and so that the teeth of the respective sets engage alternately with the teeth of the crown wheel. In the continuous rotation of the driving shaft 6 by its crank 8, the alternate engagement of the respective sets of teeth 13 and 14 with the teeth of the crown wheel cause alternate to and fro partial rotations of the crown wheel. The teeth 14 are longer or of greater radial extension than the teeth 13 so that in their engagement with the teeth of the crown wheel, the teeth 14 will move the crown wheel a greater angular distance than is effected by the engagement of the teeth 13.

The spindle 2 is adapted to carry the bit for engaging the valve to be ground. Said bit may consist of a blade 18 pivoted on pin 19 at the lower end of a stem 20, said stem being screw-threaded and screwing into a sleeve 21 which is secured to the lower end of the spindle 2. Said sleeve 21 is preferably screw-threaded to screw onto a reduced screw-threaded portion 22 at the lower end of the spindle 2, and to jam against a shoulder 23 on said spindle. A ball-bearing 24 is provided in an annular recess 25 at the bottom of the body 1, said ball-bearing engaging with the top of said recess, and with the top of the sleeve 21 to take the vertical thrust.

Referring to Fig. 1, the casing of an en-

gine is indicated at 29, said casing having opening 26 normally closed by suitable means not shown, and providing for access to valve head 27 which seats on a seat 28, the object of the grinder being to rub said valve head on its seat in such manner as to true up the surfaces. The valve head is provided with a cut or groove 30 adapted to be engaged by the bit of the grinder.

10 The grinder is used as follows: The bit, having been secured to the spindle 2 as above described, is inserted through the opening 26 and engaged with the groove 30 in head 27, the grinder being held in this position by 15 holding the handle portion 5 so as to hold the bit in vertical position while the crank 8 is being operated. The shaft 6 is rotated by operation of crank 8 and as each tooth 14 engages with and between the teeth 12 of 20 the crown wheel 11, it turns the spindle 2 forwardly a definite distance, and after such arm or tooth 14 passes out of engagement with the crown wheel, an arm or tooth 13 engages with the teeth 12 of the crown wheel 25 at the other side of the center and turns the spindle 2 a certain amount in the reverse direction, this reverse partial rotation of the spindle being less than the forward rotation by the tooth 14 by reason of the teeth 30 13 being shorter than the teeth 14. To provide for such engagement of the teeth, it is necessary that the teeth 12 of the crown wheel should be of sufficient depth to permit meshing or engagement of the longer 35 teeth 14 therewith and deeper than is required for the teeth 13 as the shorter teeth 13 do not reach as far between the crown wheel teeth as do the longer teeth 14. By continuous rotation of the driving shaft 6 40 an alternate forward and back movement is imparted to the spindle 2 and to the valve head connected thereto, and at the same time the valve head is given an intermittent progressive forward rotation, thereby equalizing the grinding action throughout its surface. By the above described construction I am able to provide this differential movement of the valve operating spindle by continuous rotation of a shaft extending at 45 50 right angles to said spindle, this construction being of advantage in that the operating crank or handle is thereby maintained in the most convenient position for operation. As shown in Figs. 7 and 8, the two 55 sets of teeth may be arranged on different sleeves indicated at 34 and 35, fastened to the shaft by separate set-screws 36. There may be any desired number of teeth or arms in each set, for example, one in each set as

shown in Fig. 7, two in each set as shown in Fig. 8, or three or more in each set as may be desired. In each case, however, the teeth or arms in each set are arranged angularly equidistant and alternately or staggered with relation to the teeth in the other set so that the teeth of the respective sets engage alternately with the teeth of the crown wheel.

What I claim is:

1. A valve grinder comprising a frame, 70 a spindle, rotatably mounted in said frame, a driving shaft journaled in the frame at right angles to the axis of the spindle, a wheel on the spindle provided with crown teeth and sets of teeth mounted on the driving shaft to engage the teeth of the crown wheel at opposite sides of the axis of the spindle, the teeth of the respective sets being arranged in different angular positions on the shaft to engage the crown wheel at different times so as to produce alternate forward and backward partial rotation of the crown wheel and spindle, and the teeth of one set being longer than the teeth of the other set and extending farther between the teeth of the crown wheel, to effect a greater angular rotation of the crown wheel by engagement of the longer teeth than is effected by the engagement of the shorter teeth.

2. A valve grinder comprising a frame, a 90 spindle rotatably mounted in said frame, a driving shaft journaled in the frame at right angles to the axis of the spindle, a wheel on the spindle provided with crown teeth, a sleeve secured to the driving shaft 95 and sets of teeth on said sleeve to engage the teeth of the crown wheel at opposite sides of the axis of the spindle, the teeth of the respective sets being arranged in different angular positions on the shaft to engage the 100 crown wheel at different times so as to produce alternate forward and backward partial rotation of the crown wheel and spindle, and the teeth of one set being longer than the teeth of the other set and extending 105 farther between the teeth of the crown wheel, to effect a greater angular rotation of the crown wheel by engagement of the longer teeth than is effected by the engagement of the shorter teeth.

In testimony whereof, I have hereunto set my hand at Los Angeles, California, this 13th day of November, 1911.

NOAH E. MEREDITH.
